UNITED STATES PATENT OFFICE.

FRANK BLANDO, OF NEW YORK, N. Y.

BALL PROJECTOR.

1,419,539.

Specification of Letters Patent. Patented June 13, 1922.

Application filed October 11, 1921. Serial No. 507,098.

To all whom it may concern:

Be it known that I, FRANK BLANDO, a citizen of the United States, residing at New York, in the county and State of New York, 5 have invented certain new and useful Improvements in Ball Projectors, of which the following is a full, clear, and exact specification.

This invention relates to toy ball projectors, shooters or throwers and has for its 10 object to provide a device of this kind which is simple in construction and easy to operate.

A special object of the invention is to provide means for retaining the ball in 15 proper engagement with its projecting or propelling slide while the latter is being drawn back along the base plate of the device for tensioning the operating spring. The invention also contemplates the provision of ball-retaining means which automatically frees the ball when the slide is 20 released, so that said retaining means will not retard the movement of the ball as it is projected by said slide. Other objects will 25 appear as the description proceeds.

The invention will be first hereinafter described in connection with the accompanying drawings which constitute part of this specification, and then more specifically defined 30 in the claims at the end of the description.

In the accompanying drawings, wherein similar reference characters are used to designate corresponding parts throughout the several views:

35 Figure 1 is a plan view of a ball projector constructed substantially in accordance with this invention, the slide being shown in its forward position.

Figure 2 is a side view of the device showing 40 the slide drawn back and the ball-retaining device in position for holding the ball in solid lines, the ball-releasing position of said device being indicated in dotted lines, and

45 Figure 3 is an under plan view of the ball projector with the parts in the position shown in Figure 1.

The device illustrated consists of a base plate 1 having a longitudinal slot 2 extending centrally thereof and a depending handle 3 near its front end. A ball-projecting slide 4 is guided in said slot 2 by a block 5 fitting loosely therein and retained in position by a cross pin 10 or any other suitable means 50 arranged below the base plate. Said block 55 is connected at 6 to the rear end of a coiled

spring 7 having its front end secured at 8 to the upper end portion of the handle 3, said spring extending along the under face of the base plate 1. When contracted said 60 spring is arranged in a housing 9 suitably secured below the base plate adjacent the handle 3.

The slide 4 carries a curved or channeled plate 11 at its forward end forming a ball-holding pocket in which the ball 12 is arranged when it is to be projected, as shown in Figure 2. In order to retain the ball in proper engagement with said channeled plate or pocket as the slide is being withdrawn and even when the base plate is held in a forwardly and downwardly inclined position as illustrated in Figure 2, a ball-retaining loop 14 is provided. Said loop is hinged at 15 to a bracket 13 on the slide 4 70 and has a downwardly extending arm 16 having its lower end hinged at 17 to the forward end of a trigger 18 which is guided at 20 on the upper face of the slide 4. Said trigger 18 has a finger loop 19 at its rear 80 end by means of which the ball-retaining loop 14 may be lowered into engagement with the ball 12 simultaneously with the rearward movement of the slide 4. It will be noted from the showing in Figure 2 that 85 the initial rearward movement of the trigger 18 will move the loop 14 down into engagement with the ball 12 until said loop rests upon the upper edge of the channeled plate 11, after which further rearward pressure 90 on the trigger will move the slide 4 along the slot 2 in the base plate 1 until the spring 17 has been properly tensioned to project the ball.

When the trigger is released, the slide is 95 moved quickly forward by the spring 7, and the loop 14 is automatically raised to release the ball 12 by a spring 22 connected at one end to the upper edge of the channeled plate 11 and at the other end to the arm 16. It 100 will thus be seen that the ball-retaining device will not interfere at all with the proper projection of the ball, the spring 22 acting immediately upon the release of the trigger so as to free said ball while the slide is moving along the slot 2 under the influence of the spring 7.

If desired, the slide may be drawn back by means of the pin 23, in which case the ball-retaining means will not be brought into 110 play, the same remaining in the dotted line position shown in Figure 2. This mode of

operating the device may be employed when the base plate is inclined forwardly and upwardly to a sufficient degree to retain the ball in place in the pocket of the channeled plate 11 by gravity.

In operating the device the handle 3 is gripped by one hand of the operator and the loop 19 or pin 23 engaged by a finger of the other hand, whereupon the slide 4 may be moved rearwardly for tensioning the spring 7. The base plate 1 may be held in a horizontal position or inclined with its front end either up or down according to the direction in which the ball is to be projected.

I claim:

1. In a ball projector, the combination with a base plate, of a slide mounted thereon, resilient means for moving said slide along the base plate in one direction, means for retaining a ball in engagement with the slide while the latter is moved in the other direction and said resilient means is being tensioned and means for automatically freeing said ball from said retaining means when the slide is released.

2. In a ball projector, the combination with a base plate, of a slide mounted thereon, resilient means for moving said slide forwardly along the base plate, a ball-retaining member mounted on said slide to hold the ball in engagement therewith when the slide is moved rearwardly, a trigger mounted on the slide for moving said retaining means into engagement with the ball as the slide is moved rearwardly, and means for automatically removing said retaining means from engagement with the ball when said slide is released.

3. In a ball projector, the combination with a base plate, of a slide mounted thereon, resilient means for moving said slide forwardly along the base plate, a ball-retaining member hinged on said slide, a trigger for swinging said ball-retaining member into engagement with the top of a ball for retaining it in engagement with the slide while the latter is moved rearwardly, and means for automatically swinging said ball-retaining member away from the ball for freeing the same when said slide is released.

4. In a ball projector, the combination with a base plate, of a slide mounted thereon, resilient means for moving said slide forwardly along the base plate, a ball-retaining member hinged on said slide and

adapted to engage the top of a ball when the latter is engaged with the slide, an arm on said ball-retaining member, a trigger connected to said arm for moving said member into engagement with the ball while the slide is moved rearwardly, and resilient means connected to said arm and to the slide for automatically moving said retaining means away from the ball when the slide is released.

5. In a ball projector, the combination with a base plate, of a slide mounted thereon, resilient means for moving said slide forwardly along the base plate, a channeled plate mounted on the slide to form a pocket for a ball, a ball-retaining member hinged on the slide to engage the top of the ball when arranged in said pocket, the downward movement of said retaining means being limited by the upper edge of said channeled plate, a trigger for moving said retaining member into engagement with the ball when the slide is moved rearwardly, and means for automatically moving said member away from the ball when the slide is released.

6. In a ball projector, the combination with a base plate, of a slide mounted thereon, resilient means for moving said slide forwardly along the base plate, a channeled plate mounted on the slide to form a pocket for a ball, a ball-retaining member hinged on the slide to engage the top of a ball arranged in said pocket, an arm on said member, a trigger connected to said arm for swinging said member into engagement with the ball when the slide is moved rearwardly, and a spring connected at one end to said arm and at the other end to said channeled plate for automatically moving said member away from the ball when the slide is released.

7. In a ball projector, the combination with a base plate, of a slide mounted thereon, resilient means for moving said slide forwardly along the base plate, a ball-retaining member mounted on the slide, means for engaging said member with a ball and also moving the slide rearwardly, means for automatically removing said member from engagement with the ball when the slide is released, and means for moving said slide rearwardly without actuating said ball-retaining member.

In testimony whereof I have signed my name to this specification.

FRANK BLANDO.
